UNITED STATES PATENT OFFICE

LE ROI EARLE HUTCHINGS AND JOSEPH D. LEAR, OF BUFFALO, NEW YORK, ASSIGNEES,
BY MESNE ASSIGNMENTS, TO REMINGTON RAND, INC., OF NEW YORK, N. Y., A
CORPORATION OF DELAWARE

FILING DRAWER

Application filed February 15, 1927. Serial No. 168,455.

This invention relates to filing drawers, and has reference more particularly to a filing drawer in which a series of pockets is slidably suspended for the reception of 5 reference data.

An object of this invention is to provide a drawer of the class described in which rods are incorporated in the drawer structure for detachably supporting on cross bars 10 carrying pockets for the reception of reference data.

A further object of the invention is to provide a drawer for holding slidably mounted reference pockets in which an easy 15 method of assembling the drawer is provided; also to improve filing drawers in other respects hereinafter specified and claimed.

Reference is to be had to the accompanying drawing forming a part of this specification, in which,

Fig. 1 is an elevation of our improved filing drawer,

Fig. 2 is a perspective of a portion of the 25 improved file drawer showing the method of assembling of the slide members,

Fig. 3 is a transverse sectional elevation through one side portion of the improved drawer,

Fig. 4 is another transverse sectional elevation through the drawer showing the pockets and cross bars in place,

Fig. 5 is a horizontal fragmentary sectional view through the drawer, and

Fig. 6 is a fragmentary plan view of the 35 rear corner of the improved drawer.

Referring to the drawing by numerals, 10 indicates the front wall, 11 the bottom, 12 the side walls and 13 the rear wall of our improved file drawer. This drawer is 40 preferably constructed of sheet metal, such as sheet steel, and is especially adapted for the reception of separators, pockets or folders 14 which are suspended from cross-bars 15. The pockets 14 may be in the form of a continuous strip of material such as cloth which is folded over the cross-bars 15 and secured thereto.

In order to slidably support the cross- 50 bars 15 at the proper height in the drawer,

a pair of slide members 16 are provided, one above each side wall 12. These slide members 16 are preferably formed of spring steel wire and the forward end of each member 16 has an upwardly extending arm 55 17 terminating in a transversely extending arm 18. In order to support the forward end of each member 16, an inwardly extending flange 19 is formed on each of the two vertical edges of the front wall 10, said 60 flange 19 being spaced apart from said front wall a distance somewhat greater than the thickness of arm 17. A notch 20 is formed in each of the flanges 19 and each notch is adapted to receive the forward end 65 of one member 16, each member being maintained in place in its respective notch by one of the inwardly extending flanges 21 formed on the two vertical edges of liner 22. This liner 22 is preferably formed at its upper edge with an offset flange 23 which extends under a downwardly extending flange 24 formed along the upper edge of front wall 10. The liner 22 is preferably assembled by first inserting the flange 23 under flange 70 24 and then forcing the bottom of said liner forwardly until it wedges tight with the bottom edge of said liner against the bottom 11 of the drawer. The tight fitting liner 22 then holds the members 16 in place, 80 and said members are prevented from twisting due to the laterally extending arm 18 engaging in front of flange 19.

The rear corner of the drawer is preferably constructed as shown in Fig. 6 in 85 which the rear edge of each side wall 12 is bent inwardly to form a flange 25. The rear wall 13 of the drawer may be formed by bending the end of the drawer bottom 11 upwardly and the flanges 25 are spot-welded 90 or otherwise secured to said rear wall 13. A socket 27 is formed in each rear corner of the drawer by bending the rear wall 13 inwardly and then outwardly outside the spot weld. In order to support the rear end 95 of slide member 16, a vertical standard 28 is inserted in the socket 27, said standard being preferably formed of a heavy piece of resilient spring wire. The upper end of standard 28 is formed into a loop 29 and 100

the rearward end of each member 16 extends through said loop 29, the extreme end of said member 16 having an upset head 30 which prevents forward disengagement or movement of the member 16 through said loop 29. The spring wire 16 preferably bows somewhat upwardly in the center as shown in Fig. 1, so that the pockets 14 are supported at the correct height above drawer bottom 11. As the pockets 14 become heavily loaded with reference data, the bottoms of said pockets flatten out and rest squarely on the drawer bottom 11 due to the fact that the member 16 flattens out under the weight of the material supported. This upward bowing of the member 16 may be aided by the upwardly extending arm 17 which engages the inward face of the flange 19 and serves to resist the downward deflection of the center of the member 16 under the weight of the reference data.

The liner 22 is spaced apart from the front wall 10 to form a compartment 31 which may contain latch mechanism, not shown, connected to a handle 32 on the front wall of said drawer. The upper edge of each side wall 12 may be formed into an outwardly extending flange 32 and then folded to form an inwardly extending flange 33, said flanges 32 and 33 serving to strengthen the side walls 12.

The provision of the interengaging parts on the slide members and the drawer permits the ready insertion of the slide members and their suspended pockets in a drawer, and also facilitates the installation of the slide members in previously used drawers.

The flanges 19 on the drawer front together with the liner 22 with the notch 20 formed in the flange 19, provide what may be termed sockets, at the opposite sides of the drawer which receive the preformed ends 17 and 18 on each slide member 16. The liner 22 also forms a locking plate for releasably locking the preformed ends of the slide members in the sockets, this liner or locking plate being detachably mounted in the drawer and retained in position by frictional engagement between the edges of the flanges 19 and the bottom 11. The interlocking connection formed at the upper edge of the drawer and the drawer front operates with this frictional engagement of the sides and bottoms so that this plate is efficiently retained in position. With this character of construction, substantial utility is embodied in the construction of a file drawer for practical use in filing cabinets so that the cabinets and drawers may be constructed and sold without the slide members or the cross-bars 15 carrying the pocket-forming strip. Thus, when the purchaser of such file cabinets finds some particular use for a sectional pocket-forming construc-

tion as shown in the drawing to divide the drawer into a series of flexible independent pockets, the attachment of the slide members 16 and the subsequent positioning of the cross-bars 15 in operative position thereon can be accomplished without modifying the construction of the drawer. This is done by removing the liner or locking plate 22, inserting the standards 28 into the sockets at the rear ends of the drawer and then inserting the ends 17 and 18 and the adjacent portion of the slide member into the sockets at the front ends of the drawer with the parts 16 extending through the notches 20. By replacing the locking plate 22, the slide members are thus held in completely assembled relation in the drawer and the cross-bars 15 by means of the slotted ends formed as shown in Figure 4 may then be applied with the strip 14 so that the file drawer is immediately adapted to the advantages obtained by the use of the strip 14 formed into a series of pockets supported by the cross-bars 15. It is to be further understood that the standards 28 may be made integral with the rear ends of the slide members 16, if desired.

We would state in conclusion that while the illustrated examples constitute preferred embodiments of our invention, we do not limit ourselves precisely to the details herein described, since manifestly the same can be considerably varied without departing from the spirit of the invention as defined in the appended claims.

We claim:

1. A filing drawer having a front wall and having a socket formed adjacent each rear corner thereof, vertical standards adapted to be positioned in each socket, a pair of slide members, each supported at one end by said standards and at the other end by said front wall, cross-bars slidably mounted on said slide members and a pocket-forming member for reference data suspended from said cross-bars.

2. A filing drawer having a front wall of sheet metal, an inwardly turned flange formed along each vertical edge of said front wall, each flange having a notch formed therein, a slide member supported in each notch in said flanges and comprising an upwardly extending arm formed on each slide member, each arm extending between said flange and front wall, means for supporting the opposite ends of said slide members, and means supported by said slide members dividing said drawer into a plurality of filing sections.

3. A filing drawer having a front wall of sheet metal, slide members, said front wall having notched portions adapted to receive one end of said slide members, a removable liner inside said front wall adapted to confine said slide members in said notched

portions, means for supporting the opposite ends of said slide members and means dividing said drawer into a plurality of filing sections supported by said slide members.

4. A filing drawer of sheet metal having 5 a pair of rear corner sockets, a vertical standard supported in each socket having a loop at the top, a pair of slide members having one end of each passing through and supported by said loops, an upset head formed 10 on each slide member adapted to prevent removal of said slide members from said loops in one direction, means for supporting the opposite ends of said slide members on said drawer, and means slidable on said slide members dividing said drawer into a plurality 15 of filing sections.

5. In a filing device, a drawer having front, side, bottom and rear walls being formed to provide sockets at the front and 20 rear ends of the side walls, slide members, preformed means on the ends of said slide members having detachable interlocking engagement in said sockets to support said members in spaced substantially parallel relation to said side walls, and means supported by said slide members dividing said drawer into a plurality of filing sections.

6. In a filing device, a drawer having front, side, bottom, and rear walls, formed 30 to provide sockets at the front and rear ends of the side walls, a pair of slide members, preformed means on the ends of said slide members engageable in said sockets to support said members in parallel relation at the 35 sides of the drawer, locking means detachably engaged with said drawer for locking said preformed means in said sockets, and means slidably mounted on said slide members dividing said drawer into a plurality of filing sections.

7. In a filing device, a drawer having front, side, bottom and rear walls, said front wall being formed with sockets at opposite 45 sides over said side walls, said side and rear walls being formed to provide sockets in the rear corners of the drawer, slide members having preformed means at the ends, the means at the ends of each slide member being engaged in the sockets at the front and rear of the drawer respectively, a locking plate at the front of the drawer locking said preformed means in said sockets, and means supported by said slide members dividing 50 said drawer into a plurality of filing sections.

8. In a filing drawer having a front wall formed with socket portions at opposite sides, slide members, each having one end 60 formed to engage in one of said socket portions, means supporting the opposite ends of said slide members at the rear end of the drawer, a locking plate removably engageable with the front wall for locking said 65 slide members in said socket portions, and

means supported by said slide members dividing said drawer into a plurality of filing sections.

9. In a filing device, a drawer having a front wall formed with an inwardly turned flange along each vertical edge, each flange having a notch formed therein, a slide member supported in each notch having an upward extension between the front wall and flange for normally retaining the slide member in upwardly bowed relation, means attaching the opposite ends of said slide members to the rear end of the drawer, and means slidable on said slide members dividing said drawer into a plurality of filing 70 sections. 75 80
